By Franklin P. D. Atty.

UNITED STATES PATENT OFFICE.

JOHN C. ADOLPH BISCHOFF, OF ST. LOUIS, MISSOURI, ASSIGNOR OF ONE-HALF TO FERDINAND G. UHLICH, OF SAME PLACE.

DOOR-MAT.

SPECIFICATION forming part of Letters Patent No. 593,508, dated November 9, 1897.

Application filed March 20, 1897. Serial No. 628,399. (No model.)

To all whom it may concern:

Be it known that I, JOHN C. ADOLPH BISCHOFF, a citizen of the United States, residing at the city of St. Louis, in the State of Missouri, have invented a certain new and useful Improvement in Door-Mats, of which the following is a full, clear, and exact description, reference being had to the accompanying drawings, forming a part of this specification.

10 My invention relates to a cast mat.

My invention consists in features of novelty hereinafter fully described, and pointed out in the claims.

Figure I is a top or plan view of my improved door-mat. Fig. II is a longitudinal section taken on line II II, Fig. I. Fig. III is a transverse section taken on line III III, Fig. I.

The body or middle part of the mat is composed of longitudinal bars 1 and transverse bars 2, forming an open checker-work. These bars are wedge shape in section, being thinner at their upper than at their lower edges.

Each end of the mat is formed of longitudinal bars 3, which are preferably extensions of the bars 1, and outer or end bars 4. The

upper edges of the bars 3 are notched out, the notches being of sufficient width to admit the sole of a shoe or boot, and the ends 5 of the notched part of the bars are designed to clean the sides of the shoe or boot, while the horizontal edges of the notched part of the bars and the middle checker-work is designed to clean the bottom of the shoe or boot.

I prefer to make my improved mat of metal. 35

I claim as my invention—

1. A door-mat, consisting of a checkered body part composed of longitudinal and transverse bars, and an end part composed of notched longitudinal bars, substantially as 40 set forth.

2. A door-mat, consisting of a checkered body part composed of longitudinal and transverse bars thinner at their upper than at their lower edges, and end parts composed of longitudinal notched bars, substantially as set forth. 45

JOHN C. ADOLPH BISCHOFF.

In presence of—

E. S. KNIGHT,
STANLEY STONER.
